(57) **CLAIM**

The ornamental design for a sanitary napkin, as shown and described.

DESCRIPTION

FIG. 1 is a perspective view of the sanitary napkin of our new design;

FIG. 2 is a right side view of the sanitary napkin of FIG. 1; FIG. 3 is a left side view of the sanitary napkin of FIG. 1; FIG. 4 is a top plan view of the sanitary napkin of FIG. 1; FIG. 5 is a bottom plan view of the sanitary napkin of FIG. 1;

FIG. 6 is a front view of the sanitary napkin of FIG. 1; and, FIG. 7 is a back view of the sanitary napkin of FIG. 1. The broken lines depict portions of the sanitary napkin that form no part of the claimed design.
